SHOE-FORM.

1,102,464.

Specification of Letters Patent.

Patented July 7, 1914.

Application filed November 3, 1913. Serial No. 798,933.

To all whom it may concern:

Be it known that we, JOHN YOUNGMAN and HARRY W. DRENAN, citizens of the United States, residing at Portsmouth, in 5 the county of Scioto and State of Ohio, have invented certain new and useful Improvements in Shoe-Forms, of which the following is a specification.

This invention is a device to be placed in 10 pumps and Oxford shoes to keep the same in shape after the last has been removed. Shoes of this style have a tendency to bulge out at the top, and the present invention is designed to prevent this.

15 It is the object of the present invention to provide an efficient device of the kind stated which is extremely simple, and which can be cheaply manufactured, and readily inserted into and removed from the shoe.

20 In the accompanying drawing forming a part of this specification, Figure 1 is a longitudinal section of a shoe showing the device in place; Fig. 2 is a perspective view of the device removed from the shoe, and Fig. 25 3 is a cross section of the device on the line 3—3 of Fig. 1.

Referring specifically to the drawing the device comprises a bar or stick 5, which may be of wood, and is of such length that it can 30 be placed in the shoe to extend slantingly between the forward portion of the insole and the top of the counter. The bar is enlarged slightly toward one end, as indicated at 6, and has a rounded corner 7 at which is 35 located an outstanding pin 8. The opposite or smaller end of the bar is also rounded, as indicated at 9. The pin 8 is secured to the edge of the bar in any suitable manner, and it projects in an oblique direction from 40 the bar. The edge of the bar, adjacent to the pin, is faced with a metal strip 10.

In use, the bar 5 is placed into the shoe, so as to extend slantingly between the forward portion of the insole and the back part 45 or counter of the shoe. The pin 8 is stuck into the insole and the rear end of the bar is then forced down into the shoe to come flush with the top edge thereof at the back or counter. This draws up all slack in the 50 throat and brings the shoe back to its proper shape. The rounded edge 9 allows the rear end of the bar to slip freely down into the shoe.

The device is extremely simple, in view of

which it can be easily and cheaply manufactured, it can be readily placed in the shoe and removed therefrom, and it effectually serves the purpose for which it is designed.

The part 8 may be an ordinary headed 60 tack which is fastened to the bar by a metal strip 11 fitting over the rounded edge 7 thereof and having a perforation through which the tack passes, the head of the tack being clamped to the edge of the bar by 65 the metal strip. The tack also passes through the metal strip 10, said strip serving to reinforce the rounded edge of the bar.

We claim:

1. A shoe form comprising a narrow elongated bar having a pin projecting obliquely and downwardly from one of its ends, and arranged to enter the insole rearwardly of the front thereof.

2. A shoe form comprising a narrow elongated bar of such a length as to extend slantingly between the forward portion of the insole and the top of the counter or back portion of the shoe, and a pin projecting downwardly from the forward end of the 80 bar for insertion into the insole rearwardly of the front thereof.

3. A shoe form comprising a narrow elongated bar of such a length as to extend slantingly between the forward portion of the insole and the top of the counter or back portion of the shoe, the rear counter-engaging end of the back being rounded, and a pin projecting downwardly from the forward end of the bar for insertion into the 90 insole.

4. A shoe form comprising a bar having a pin projecting obliquely and downwardly from one of its ends, and a strip fastened to the bar and extending over the edge thereof at the aforesaid end, said strip having a perforation through which the pin passes, and the pin having a head seating under the strip and clamped thereby against the edge of the bar.

In testimony whereof we affix our signatures in presence of two witnesses.

JOHN YOUNGMAN.
HARRY W. DRENAN.
